(57) **CLAIM**

The ornamental design for a recycle disposal unit, as shown and described.

DESCRIPTION

FIG. 1 is a perspective view of a recycle disposal unit showing my new design;

FIG. 2 is a top view of a recycle disposal unit illustrated in FIG. 1;

FIG. 3 is a front view of a recycle disposal unit illustrated in FIG. 1;

FIG. 4 is a left side view of a recycle disposal unit illustrated in FIG. 1;

FIG. 5 is a back view of a recycle disposal unit illustrated in FIG. 1;

FIG. 6 is a bottom view of a recycle disposal unit illustrated in FIG. 1; and,

FIG. 7 is a right side view of a recycle disposal unit illustrated in FIG. 1.

The broken line showing in the figures is included for the purpose of illustrating environment and forms no part of the claimed design.
